(57) **CLAIM**

The ornamental design for a faucet as shown and described.

DESCRIPTION

FIG. 1 is a front view of a faucet in accordance with the present application.

FIG. 2 is a top view of the faucet.

FIG. 3 is a side view of the faucet.

FIG. 4 is a first isometric view of the faucet; and,

FIG. 5 is a second isometric view of the faucet.

The broken lines are included for the purpose of illustrating portions of the faucet and form no part of the claimed design.

1 Claim, 5 Drawing Sheets

FIG. 1

FIG. 3

FIG. 4

FIG. 5
